UNITED STATES PATENT OFFICE.

MONROE KOHN, OF CHICAGO, ILLINOIS.

CUFF-LINK.

1,291,555.

Specification of Letters Patent. Patented Jan. 14, 1919.

Application filed March 25, 1918. Serial No. 224,441.

To all whom it may concern:

Be it known that I, MONROE KOHN, a citizen of the United States, residing at Chicago, county of Cook, State of Illinois, have invented a certain new and useful Improvement in Cuff-Links, and declare the following to be a full, clear, and exact description of the same, such as will enable others skilled in the art to which it pertains to make and use the same, reference being had to the accompanying drawings, which form a part of this specification.

My invention relates to that type of cuff fastening which comprises two button members detachably connected together so that the two members may be inserted independently of each other into the cuff ends and thereafter be connected together; and it has for its object to produce a simple and novel construction and arrangement which may be placed in position or removed easily and conveniently, which shall hold the cuff securely fastened, and which, when in place, shall present substantially the same appearance and give substantially the same effect as an ordinary cuff link comprising simple flat button members and a flexible connecting link.

In carrying out my invention I employ two members each comprising a head and a shank, the two shanks being constructed and arranged to be detachably connected together. In order to hold the individual members in the cuff before they are connected together and prevent them from dropping out, I provide clamping devices on the inner or under side of each of the heads; these clamping devices being made to slip easily through a button hole and then to spread out and engage the inner surface of the cuff in the vicinity of the button hole. This feature of my invention may be used to advantage in connection with collar buttons or studs, particularly those having long shanks, where it is desired to hold the base of the button or stud in close contact with a collar band or other member through which the button passes. Therefore, viewed in one of its aspects, my invention may be said to have for its object to produce a simple and novel clamping device for permitting a head member to be detachably clamped against a part through which an attached shank passes.

It is of course necessary that the clamping device be capable of occupying such a posi-

tion that it will not obstruct the entrance of the shanks of the buttons through the button holes and, viewed in one of its aspects, my invention may be said to have for its object to produce a simple clamping device of the kind specified which will pass readily through a button hole, serve to open the button hole to receive the headed or unheaded shank, and then automatically spread out on the inner side of the cuff and clamp the cuff against the button member on the outer side of the cuff.

The various features of novelty whereby my invention is characterized will herein-after be pointed out with particularity in the claims; but, for a full understanding of my invention and of its objects and advantages, reference may be had to the following detailed description taken in connection with the accompanying drawings, wherein:

Figure 1 is a view partly in side elevation and partly in section of one member of a pair of cuff links arranged in accordance with a preferred form of my invention; Fig. 2 is a side elevation of the device shown in Fig. 1, in a plane at right angles to the plane of Fig. 1; Fig. 3 is a top plan view; Fig. 4 is a section taken approximately on line 4—4 of Fig. 1, on an enlarged scale; Fig. 5 is a side elevation similar to Fig. 1, showing the complementary member; Fig. 6 is a side elevation of one member of a modified form of button or link; Fig. 7 is a side elevation in a plane at right angles to the plane of Fig. 6; Fig. 8 is a section taken approximately on line 8—8 of Fig. 6; Fig. 9 is a section on an enlarged scale taken approximately on line 9—9 of Fig. 6; Fig. 10 is a side elevation of a modified form of device; Fig. 11 is a side elevation of a still further modification; and Fig. 12 is a top plan view of the device shown in Fig. 11.

Referring to Figs. 1 to 5 of the drawings, 1 and 2 represent two button members adapted to form the outer or exposed buttons of a pair of cuff links and provided respectively with shanks, 3 and 4, projecting centrally from the inner sides thereof. At their free ends the shanks are provided with means for detachably connecting them together in a simple and convenient manner. In the arrangement shown, the shank member 3 is provided with a small head or ball, 5, while the shank, 4, has a socket, 6; the members 5 and 6 constituting an ordinary ball and socket snap fastening. On the inner side of

each of the members 1 and 2 are two fingers, 7 and 8, hinged at one end to the corresponding button member on opposite sides of the shank and overlapping at their free ends so 5 as to form a part more or less U-shaped in appearance when both of the fingers are placed upright, that is parallel with the corresponding shank. The fingers are preferably bowed in opposite directions as viewed 10 in the direction of a plane containing their pivotal axis, as shown in Fig. 2, so that when in their raised or vertical position they bulge outwardly from each other in the vicinity of the members 5 and 6 and then 15 engage each other above the members 5 and 6 so as to form a gradually swelling two-part shield for the latter. Thus, when one of the link members is to be placed in a cuff, the engaging outer or upper ends of the fingers are first inserted through the button 20 hole and, by pressing inwardly upon the button, the button hole is gradually opened so that the ball or socket member can pass readily through the same. The parts are so 25 arranged that as the fingers pass through the button hole, they are caused to swing about their pivots and assume the positions shown in dotted lines in Fig. 2, namely positions in which they project in opposite directions from the shank or post and lie substantially flat against the inner side of the cuff. In order that the fingers may be held 30 in each of their two positions and snap into their locking or clamping positions after 35 having been started by the button hole, they are preferably supported in some one of the usual ways employed in collar buttons or the like having hinged heads or guards. In the arrangement shown, each of the fingers has 40 at its base a trunnion member, 9, seated in a suitable socket, 10, stamped up out of the metal of which the inner side of the corresponding button is made; each trunnion member having on its under or inner side a 45 part, 11, having two flat faces which make an angle with each other. A spring plate or disk, 12, is arranged within each of the buttons in contact with the trunnions and the part 11 of each trunnion is so shaped 50 that whenever the corresponding finger is in its raised or vertical position one of the flat faces of the part 11 engages with the disk or plate 12 while in the clamping position of the finger the other flat face engages 55 with the spring plate or disk. In shifting a finger from one position to the other a point will always be reached from which the remainder of the shifting movement will be automatic due to the action of 60 the spring plate or disk. If the fingers are of the same height it is necessary that they cross each other in order that they may begin to move into their clamping positions when they enter the button hole. Further- 65 more, in order to secure a comparatively

thin wedge-like edge or end for entry into the button hole, the overlapping portions of the fingers, as indicated at 13, are preferably reduced in thickness so that their combined thicknesses are no greater than the thickness 70 of the main portion of one of the fingers alone.

In the arrangement shown in Figs. 6 to 9, the button member with its shank and fastening device may be the same as that heretofore described. Instead of individual fingers, two complete bails, 14 and 15, may be provided for each button; each of the bails being hinged at the ends of its arms to the button at opposite sides of and in the vicinity 75 of the shank of the button. In the arrangement shown, there is a common supporting bearing, 16, for the two bail ends on each side of the shank. Each of these bearings may consist of a piece of sheet metal 80 bent into the form of a cylinder and having free edges or ends extended through the inner member 17 of the button and bent laterally as indicated at 18 in Fig. 9. The ends of the inner bail 14 are bent outwardly, as 85 indicated at 19, so as to enter the bearing 16 from the inner ends of the latter. The ends of the outer bail 15 are bent inwardly so as to enter the bearing 16 from the outer ends. The bails are made of spring material and 90 the bearings are provided in their inner and outer ends with notches, 21 and 22, into which the adjacent portions of the bails may 95 seat themselves. The notches are so disposed that whenever the bails are in their upright 100 positions as shown in Figs. 6 and 7, they will be yieldingly held in those positions by the notches 21 whereas, when they are in their lowered or clamping positions, they are yieldingly held in those positions by 105 means of the notches 22; the springiness of 110 the bails permitting them to yield sufficiently to ride into and out of the notches and serving also to keep them seated in the notches with a sufficient degree of firmness to prevent them from being accidentally displaced. The bails are bowed in opposite directions 115 between the ends thereof so as to secure an overall width or thickness preferably as great as or greater than the largest corresponding dimension of the ball or socket or other fastening device on the end of the shank of the corresponding button.

Instead of bowing the guard members or fingers, any other means may be provided 120 for effecting an automatic shifting thereof as they pass through the button holes. Thus, in the arrangement shown in Fig. 10, there is a guard finger, 25, pivotally supported at its lower end in a bearing, 26, similar to the bearing 16 in the device shown in Figs. 7 to 9, there being a lateral projection, 27, at any suitable point along the finger, conveniently in the vicinity of the hinge axis. When the device is to be inserted through a button 130

hole, the finger is placed in the position shown in full lines and, as the fabric in the vicinity of the button hole strikes the projection 27, the finger is caused to be snapped 5 from the full line position into the dotted line position.

In Figs. 11 and 12 I have shown another form of my invention in which the guard, 30, is in the form of a loop or flat plate having a hole through the same, hinged as indicated at 31; in the same manner that the guard fingers in the form of my invention shown in Figs. 1 to 4 are hinged; the parts being so proportioned that in one of the two 10 positions of the guard it extends diagonally up past the top or free end of the shank and overlies the latter at its free end as shown in full lines in the drawing. As the device is passed through a button hole, the guard 15 is pressed down and snaps into the clamping position shown in dotted lines in the drawing.

It will thus be seen that I have produced a simple and novel arrangement which will 20 permit the two members of a cuff fastening to be inserted easily and conveniently through the button holes and be yieldingly locked so as to prevent them from being accidentally withdrawn or dropping out before the two ends of the cuff are brought together and the two fastening members connected. It will furthermore be seen that the 25 yieldable locking is effected automatically because of the shape of the guard fingers 30 which causes them to be snapped against the inner side of the cuff as they pass through the button hole. It will also be seen that the guard fingers serve as an entering wedge to open the button holes for the passage of the shanks and, where the shanks are headed to provide a ball and socket joint, the bowing of the guard fingers beyond the 35 enlarged portions insures that the latter will easily pass through the button holes. In 40 some instances the guards may serve as clamps although, if desired, the parts need not be so proportioned that the cuff will be actually clamped between the guards and the ornamental buttons or heads. It will also be 45 seen that my invention may be applied to a single button such as a collar button, or the like; either of the two complementary parts of the cuff fastenings illustrated serving to represent such a collar button or stud which 50 could have a head of any desired size and shape at the point where the ball or socket member is located in the arrangement shown.

In the foregoing detailed description I 55 have referred to my invention as applied to fastening devices for garments or parts of garments, but it is equally applicable to the fastening together of any members which it is now customary or which it may be desirable to connect together by means of buttons 60 and button holes. An example of such a use

is the attachment of curtains for automobiles or carriages.

While I have illustrated and described with particularity only a single preferred form of my invention, with a slight modification, I do not desire to be limited to the exact structural details thus illustrated and described; but intend to cover all forms and arrangements which come within the terms employed in the definitions of my invention 75 constituting the appended claims.

I claim:

1. A button having a head and a shank, a combined clamping and guide member hinged to the button at a point below said 80 head and adapted to swing from a position in which it extends in the general direction of the shank to a position in which it extends transversely of the shank, the length of said member being such that when it extends in the general direction of the shank 85 it projects beyond the head of the button so as to enter a button hole in advance of the button head.

2. A button having a head and a shank 90 and a clamping member hinged to the button at a point below the head and adapted to swing from a position in which it extends in the general direction of the shank to a position transverse of the shank, said clamping member being constructed and arranged 95 to be automatically forced from the first mentioned position to the other position by the material surrounding a button hole through which the head of the button is 100 passed.

3. A button having a head and a shank and two clamping members hinged to the button below the head and adapted to swing 105 from positions in which they extend in the general direction of the shank to positions transverse to the shank, said clamping members being of such length that when they extend in the general direction of the shank they project beyond the head of the button 110 and enter the button hole in advance of the head.

4. In a device of the character described, a head or button, two clamping members hinged to the same and adapted to swing 115 from a position approximately at right angles to the plane of the button or head to a position approximately parallel to said plane, said clamping members being bowed outwardly in opposite directions from a 120 plane containing the hinge axes and extending at right angles to the aforesaid plane.

5. In a device of the character described, a head or button, two clamping members hinged to the same and adapted to swing 125 from a position approximately at right angles to the plane of the button or head to a position approximately parallel to said plane, said clamping members being bowed outwardly in opposite directions from a 130

- plane containing the hinge axes and extending at right angles to the aforesaid plane, and means for holding said members yieldingly in each of their aforesaid positions.
- 5 6. In a device of the character described, a head or button, two clamping members hinged to the same and adapted to swing from a position approximately at right angles to the plane of the button or head to a position approximately parallel to said plane, said clamping members being bowed outwardly in opposite directions from a plane containing the hinge axes and extending at right angles to the aforesaid plane,
- 10 15 and means for yieldingly holding said members in each of the aforesaid positions and causing them to move into either of said positions when brought to a predetermined point from the other position.
- 15 20 7. In a device of the character described, comprising two button members each having a head and a shank, means at the free ends of the shanks for detachably connecting them together, two guard fingers hinged to each of said members so as to be capable of swinging about an axis transverse to the corresponding shank from a position in which they extend in the general direction of the shank to positions in which they ex-
- 25 30 35 tend transversely of and in opposite directions from the shank, said fingers being made of such length and being so shaped that when in the upright position they extend across the free end of the corresponding shank and serve as a guide in entering the shank into a button hole.
- 30 35 40 45 50 55 8. In a device of the character described, comprising two button members each having a head and a shank, means at the free ends of the shanks for detachably connecting them together, two guard fingers hinged to each of said members so as to be capable of swinging about an axis transverse to the corresponding shank from a position in which they extend in the general direction of the shank to positions in which they extend transversely of and in opposite directions from the shank, said fingers being made of such length and being so shaped that when in the upright position they extend across the free end of the corresponding shank and serve as a guide in entering the shank into a button hole, and the guard fingers on each of said members being bowed in opposite directions in planes transverse to their hinge axis.
- 55 9. In a device of the character described,

comprising two button members each having a head and a shank, means at the free ends of the shanks for detachably connecting them together, two guard fingers hinged to each of said members so as to be capable of swinging about an axis transverse to the corresponding shank from a position in which they extend in the general direction of the shank to positions in which they extend transversely of and in opposite directions from the shank, said fingers being made of such length and being so shaped that when in the upright position they extend across the free end of the corresponding shank and serve as a guide in entering the shank into a button hole, the guard fingers on each of said members being bowed in opposite directions in planes transverse to their hinge axis, and means associated with each of said guard fingers for holding it yieldingly in each of its aforesaid positions and permitting it to snap from one position to the other after being carried to a predetermined point.

10. A button having a head and a shank, said shank having an enlargement at its free end, and a guard hinged to the button at a point below said enlargement and adapted to swing from a position in which it extends in the general direction of the shank to a position in which it extends transversely of the shank, said member having a part projecting laterally so as to lie a considerable distance at one side of a line passing through the hinge axis and parallel with the shank and adapted to be engaged by the material beside a button hole to swing the guard from one position to the other when it is passed through a button hole.

11. A device of the character described, comprising two members each having a head and a shank, means at the free ends of the shanks for detachably connecting them, and a guard finger hinged on each of said members so as to be capable of swinging from positions in which they extend in the general directions of the shanks to positions in which they lie transversely of the shanks, each guard finger having a part projecting laterally to be engaged by the material beside a button hole and cause the finger to be swung into its transverse position after passing through a button hole.

In testimony whereof I sign this specification.

MONROE KOHN.
